DUAL LIGHTING FIXTURE

Ralph E. Paulson, 14802 Grevillea Ave.,
Lawndale, Calif. 90260

Filed Apr. 9, 1973, Ser. No. 349,012

Term of patent 14 years

Int. Cl. D26—05; D25—01
U.S. Cl. D48—23 R

FIG. 1 is a front top perspective view of the dual lighting fixture showing my new design, the undisclosed rear view is the same in appearance as the front view shown;

FIG. 2 is a fragmentary front elevational view thereof, the fixture being partially broken away to disclose the interior structure of my new design.

FIG. 3 is a cross-sectional view of FIG. 2 taken along lines 3—3;

FIG. 4 is a bottom front perspective view of the dual lighting fixture showing my new design;

FIG. 5 is a fragmentary top plan view thereof; and

FIG. 6 is a fragmentary bottom view thereof.

The fixture is fragmentarily shown in FIGS. 2, 5 and 6 for convenience of illustration.

I claim:

The ornamental design for a dual lighting fixture, substantially as shown and described.
